UNITED STATES PATENT OFFICE.

THOMAS A. DE VILBISS, OF TOLEDO, OHIO, ASSIGNOR TO THE DE VILBISS MANUFACTURING COMPANY, OF TOLEDO, OHIO, A CORPORATION OF OHIO.

ATOMIZER OR THE LIKE.

1,093,039.

Specification of Letters Patent. Patented Apr. 14, 1914.

Application filed October 25, 1913. Serial No. 797,299.

To all whom it may concern:

Be it known that I, THOMAS A. DE VILBISS, a citizen of the United States, and a resident of Toledo, in the county of Lucas and State of Ohio, have invented a certain new and useful Atomizer or the like; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates particularly to valves for atomizers and similar instruments, but is not restricted to such use as it may be used in any connection for which it may be adapted or appropriate.

20 The primary object of my invention is the provision, in an instrument of this character, of improved means for carrying the spray parts to permit an axial turning thereof to facilitate the directing of a spray in different directions, and which is also operable to close the communication between the interior of an associated liquid receptacle, the spraying parts and the atmosphere, whereby to facilitate a packing of such instruments 25 in traveling cases or the like without removing the liquid contents of the instruments and without danger of leakage of such contents to the injury of articles packed therewith.

30 35 The invention is fully described in the following specification, and while, in its broader aspect, it is capable of embodiment in numerous forms, a preferred embodiment thereof is illustrated in the accompanying drawings, in which.—

Figure 1 is a side elevation of an instrument embodying my invention with the spraying parts adjusted relative to the carrying head for lateral horizontal spraying. Fig. 2 is a cross-section of the invention on the line α , α in Fig. 4 with parts broken away. Fig. 3 is a side elevation of the movable valve member with the attached tubes broken away. Fig. 4 is a central longitudinal vertical section of the carrying head and associated parts with the valve in open position, and Fig. 5 is an elevation of the valve plug turning collar mounted on the valve plug with the securing nut removed.

55 Referring to the drawings, 1 designates

the liquid receptacle of an atomizer or similar instrument, and 2 a head for closing the neck of the receptacle, as by threading into a ferrule or sleeve 3 secured to the open top or neck thereof. The head 2 is provided horizontally therethrough, or in transverse relation to the receptacle neck, with a preferably tapered or slightly conical passage or opening 4 into which a valve plug 5 of complementary tapered or conical form is mounted for rotary adjusting movements therein. Two tubes 6 and 7, which for convenience may be designated the air and liquid tubes, respectively, of the instrument, project longitudinally from the larger end of the valve 60 plug 5 and terminate at their outer ends in a common spray head 8, which, in the present instance, is pivotally carried by the tubes to permit an adjustment thereof relative to the tubes to facilitate a discharging of liquid 65 in spray form in a direction longitudinally of said tubes or transversely thereof.

It is to be understood that the invention is not restricted to the use of any particular form of nozzle but contemplates broadly the use of any type of nozzle adapted for a lateral discharge of spray or fluid over the tubes 6 and 7. A passage 9 is provided longitudinally through the valve plug 5 from one end to the other thereof with one end 70 opening into the inner end of the tube 6 and with its other end opening without the small end of the valve plug axially thereof to adapt it to have communication with a source of fluid, such for instance, as air 75 under pressure. The liquid tube 7 has the inner end of its bore opening into a passage 10 in the valve plug, such passage extending rearwardly therein from the tube 7 to adjacent the center of the head 2 and is thence 80 forked to form the two laterally extending branches 10^a and 10^b, which open without the side of the valve plug in position for one or the other thereof to register with the liquid supply passage 11 in the lower portion of the head 2 when the valve is in two different positions of its rotary adjustment. The outer ends of the branch passage 10^a and 10^b are disposed one-quarter of a turn 85 apart, in the present instance, so that one 105 will register with the supply passage 11 when the plug 5 is turned in position to place the tubes 6 and 7 in horizontally 90 spaced relation, and the other will register with the supply passage when the plug is 95 110

turned to place said tubes in vertically spaced relation. The supply passage 11 is provided in the lower portion of the head 2 and is extended to near the bottom of the 5 receptacle by a tube 12, which is threaded at its upper end into the lower end of the head portion of the passage.

A small needle-prick opening 13 extends laterally from the fluid passage 9 of the 10 valve plug into communication with a segmental groove 14 extending circumferentially of the plug. The groove 14 has communication with the atmosphere through a vent channel 15 in the upper portion of the 15 head 2, the lower end of such channel being in register with the groove and has communication with the interior of the receptacle through a channel 16 in the lower portion of the head 2 when either of the branch 20 passages 10^a or 10^b is in register with the supply passage 11. The groove 14 terminates at one end adjacent to the channel 16 so that when the valve plug is turned in counter-clockwise direction (referring to 25 Fig. 1) the groove moves out of register with the channel 16, thereby closing the communication between the interior of the receptacle and the air supply passage 9 of the valve plug.

30 It will be evident from this construction that when either of the passages 10^a or 10^b is in register with the liquid supply passage 11 in the head the interior of the receptacle will be in communication with the atmosphere through the restricted channels 15 and 16 and connecting groove 14, thus preventing a vacuum from occurring in the receptacle upon the discharge of liquid therefrom. Air under pressure is also supplied 35 to the interior of the receptacle when the instrument is being operated due to the restricted communication 13 between the passage 9 and groove 14. The purpose of the restricted communication between the passage 40 9 and the interior of the receptacle is to permit a "flooding" of the spray parts of the instrument when air pressure is present in the passage 9 and the channel 15 is closed, as by placing a thumb thereover, thus causing 45 a portion of the air which is being forced through the passage 9 to pass therefrom into the interior of the receptacle to cause an air pressure upon the top of the fluid within the receptacle.

50 The valve plug 5 is provided at its small end with a neck or reduced portion 17 which projects beyond the head 2 when the plug is seated therein and terminates in threads 55 18. A collar 19, which preferably has a knurled edge to facilitate a hand turning thereof, is placed over the extension 17 with its inner end or side abutting against the head 2 and is prevented from turning relative to the extension 17 by having coacting 60 portions thereof flattened, as shown at 20 in

Fig. 5, or engaging in any other suitable manner. A nut 21 is secured onto the threaded end portion 18 of the extension 17 and serves to hold the collar 19 in position on such extension, and in addition forms a 70 continuation of the passage 9 and a heel piece for the attaching of an air pressure supply tube thereto. The inner end of the collar 19 is counterbored, as at 22, to receive a coiled compression spring 23, which has one end-thrust against the collar and its other end-thrust against the adjacent side of the head 2, and coacts with the collar to yieldingly hold the valve plug 5 to its seat within the head opening. 80

The rotary movements of the valve plug 5 relative to the head 2 are limited, in the present instance, to a half turn due to a stop pin 24 projecting laterally from the large 75 end portion of the valve plug into a recess 25 in the adjacent side of the head, such recess being of suitable length for such purpose.

It is evident in the use of my improved valve that when the same is turned to the right from the position noted in Figs. 2 90 and 4 both of the passages 10^a and 10^b will be out of register with the supply passage 11 and the channel 15-16 will be closed to the groove 14, thus preventing an escape of liquid from the receptacle should it be inverted or placed on its side. When the passage 10^a is in communication with the liquid supply passage 11 the spraying parts are in position for directing a spray in a horizontal or transverse direction relative to the receptacle, and when the passage 10^b is in communication with said supply passage the spray parts are in position for directing a spray either upwardly or forwardly relative to the instrument. 100

Having thus described my invention, what I claim as new, and desire to secure by Letters Patent, is,—

1. In a device of the class described, a receptacle, a closure head for said receptacle 110 having an opening transversely therethrough and a liquid supply passage leading transversely from said opening, a valve plug rotatably mounted in said opening and having a longitudinally extending air passage 115 therethrough and a liquid supply passage in communication with the supply passage in said head when the valve plug is in one position relative to the head, and means for opening communication between said air 120 passage and the interior of the receptacle when the liquid passages of the plug and head are in register.

2. In a device of the class described, a receptacle, a closure head for said receptacle 125 having an opening transversely therethrough and a liquid supply passage leading transversely from said opening, a valve plug rotatably mounted in said opening and having a longitudinally extending air passage 130

therethrough and a liquid passage opening without an end of the valve plug and registering with said supply passage when the plug is turned in one position relative to the head, and means for opening communication between the interior of the receptacle and the atmosphere and said air passage when the valve plug is in one position and for closing such communication when the valve plug is in another position relative to the head.

3. In a device of the class described, a receptacle, a closure head for said receptacle having an opening therethrough and a liquid supply passage leading to one side of said opening, a valve plug rotatably mounted in said opening, a liquid tube and an air tube extending from an end of said valve plug and terminating at their outer ends in a common nozzle, said air tube having communication through the valve plug with a source of air supply and said liquid tube having communication through the valve plug with said liquid supply passage when the plug is in predetermined positions relative to the head, and means for supplying air to the interior of the receptacle both from the atmosphere and from said air passage when the valve plug is in position for its liquid passage to register with said supply passage.

4. In a device of the class described, a receptacle, a closure head for said receptacle having a transverse opening therethrough and having a liquid supply passage leading from the interior of the receptacle to a side of said opening, a valve plug rotatably mounted in said opening and having a circumferentially extending segmental groove and separate air and liquid passages extending through portions thereof, said air passage being adapted to have communication with a source of air supply and said liquid passage having communication with said supply passage when the plug is in predetermined positions of its movement relative to the head, tubes extending respectively from the air and liquid passages of the plug and terminating at their outer ends in a common nozzle, said groove having permanent communication with the air passage and having communication with the interior of the receptacle capable of being interrupted by a predetermined turning of the valve plug within the head.

5. In a device of the class described, a receptacle, a closure head for said receptacle having a transverse opening therethrough and having a liquid passage and an air channel leading from a side of said opening into the receptacle, and also having a channel

leading from said opening to the atmosphere, a valve plug rotatably mounted in said opening and having an air passage therethrough and a liquid passage with one end branched and each branch positioned to register with said liquid supply passage when the plug is in different predetermined positions relative to the head, said valve plug also having a segmental circumferential groove in register with both of the channels in said head when either branch of the liquid passage is in register with said supply passage and also having restricted communication with said air passage, said groove being movable out of register with the air channel in communication with the receptacle when the valve plug is at a predetermined position of its movement relative to the head.

6. In a device of the class described, a head having a liquid supply passage and an atmospheric vent passage therein, a valve rotatably mounted in said head and having a liquid passage and an air pressure supply passage in respective communication with said liquid supply passage and said vent passage when the valve is in a predetermined position of its rotary movement relative to the head, and air and liquid tubes carried by said valve for movements therewith and having communication respectively with the air supply and liquid passages of the valve.

7. In a device of the class described, a head having a liquid supply passage and an atmospheric vent passage therein, a valve mounted for rotary movements in said head, and having air pressure supply and liquid passages therein and a bypass from said air supply passage, said valve closing said liquid supply passage and interrupting said vent passage when in one position of its rotary movement relative to the head and opening said vent passage and placing it in communication with the air supply passage and also opening communication between the liquid passage of the valve and the liquid supply passage of the head when the valve is in a different position of its rotary movement, and air and liquid tubes carried by said valve for movements therewith and having their bores in respective communication with the air supply and liquid passages of the valve.

In testimony whereof, I have hereunto signed my name to this specification in the presence of two subscribing witnesses.
